Primary Examiner — Wan Laymon*(74) Attorney, Agent, or Firm* — Simpson & Simpson,
PLLC(57) **CLAIM**

The ornamental design for a gel pack, as shown and described.

DESCRIPTION

FIG. 1 is a front perspective view of the gel pack of the present invention;

FIG. 2 is a front elevational view of the gel pack shown in FIG. 1;

FIG. 3 is a rear elevational view of the gel pack shown in FIG. 1;

FIG. 4 is a left side elevational view of the gel pack shown in FIG. 1;

FIG. 5 is a right side elevational view of the gel pack shown in FIG. 1;

FIG. 6 is a top plan view of the gel pack shown in FIG. 1; and,

FIG. 7 is a bottom plan view of the gel pack shown in FIG. 1.

Stippling and/or contour lines are included in the various views, for example, FIGS. 1-7, to depict surface curvature, flatness or other shapes.
